UNITED STATES PATENT OFFICE.

HOWARD N. MOODY, OF NEW ORLEANS, LOUISIANA.

SUBMERGED MATTRESS AND SCREEN-POLE SECURING DEVICE.

Application filed May 24, 1927. Serial No. 193,884.

This invention relates to submerged mattress and screen pole securing devices for use in construction work or protecting a river bank.

This applicant is and for a number of years has been engaged as a contracting engineer in carrying out projects and work for the protection and strengthening of river banks. In so far as his knowledge and experience extends he believes the regular way this work is done is that a mattress, woven of small willow saplings, is placed over the exact position where the current of the river is to be deflected, and then the screen poles are sharpened and shoved through the mattress six inches or the like, allowing the small or upper ends of these poles to stick up high enough to come above the surface of the water, when the mattress is sunk to the bottom of the river by placing rocks upon the mattress. The screen poles are usually held in substantially vertical positions by walings or wale-pieces. The wale-pieces are arranged in spaced pairs with the poles passing between them, and the wale-pieces are fastened to the regular fixed piling. The screen poles are set some ten inches apart and they are intended to retard the flow of the water through them in such a manner as to create an eddy of water behind them, and in very silty water this retardation and eddying allows the silt to form on top of the rock ballast of the mattress and gradually build up a bar. The process above set out is an old one and has been used for the last forty years on both the Mississippi and Ohio Rivers. Numerous devices have been made and proposed at different times for securing the screen poles to the mattress and allowing the poles to stand in upright positions before the mattress is sunk. Ordinarily the ends of the screen poles have heretofore been either bolted to or laced in with the mattress by tie wires, in such a way that after the mattress is sunk and there is a recession of the river bottom before the mattress comes to its final position of rest, the screen poles will not pull loose from the mattress.

The object of this invention is the provision of means for securing the screen poles in position with respect to the mattress, in such manner that the mattress may adjust itself slightly after it has been sunk and without moving the poles after they are in final position, yet the poles cannot be pulled

out of the mattress. Two forms of devices for the attainment of the stated object are illustrated and described in this application, each has the same function as the other and either can be employed alone, or both may have to be used at different times in the same piece of work. As shown and explained both forms of screen pole securing means given as the basis of this application extend transversely below the mattress with respect to the ends of the screen poles to which such securing means are attached.

In the accompanying drawings forming a part of this application, Figure 1 represents a view partly sectional of a portion of a river bed and a portion of a construction made in accordance with this invention showing a mattress floating over a surface of a river preparatory to sinking.

Fig. 2 is a top view of the regular piling showing the upper pair of the spaced wale-pieces between which the screen poles are held.

Figure 3 is a view of the lower ends of several screen poles arranged side by side showing a cable passing through those ends.

Figure 4 is a view of the ends of a number of the screen poles as in Figure 3, showing a chain passing through the ends of the poles.

Figure 5 is a view of the ends of a number of the screen poles as in Figure 3, showing a steel rod passed through the ends of the poles.

Figure 6 represents a view similar to Figure 1, showing a portion of a river bed partly sectional, with this invention applied thereto and showing the modified form or toggle devices employed for securing the poles while permitting the relative movement of mattress and poles.

Figure 7 is a vertical section of a portion of the river bed, and of the mattress thereon, and of the lower pair of wale-pieces attached to the piling, and shows the pivoted toggles in their securing positions transversely, with respect to the ends of the screen poles below the mattress.

Figure 8 represents the lower end of a screen pole, and shows the pivoted toggle bar or member in its normal or first position arranged lengthwise of the pole.

Figure 9 is a view showing the lower end of a screen pole with the toggle in its secur-

ing position disposed crosswise with respect to the end of the screen pole.

Figure 10 is a view showing the lower end of a screen pole with a toggle bar on each side of the pole held thereon by a single bolt through the pole.

Throughout the drawings and description the same number is used to refer to the same part.

10 Considering the drawings, the river bed 1 has driven into it the regular vertical piles 2, usually connected by upper wale-pieces 3 and similar lower pieces 4. These pieces may be arranged in parallel pairs as illustrated in Figure 2.

15 In substantially vertical positions between the wale-pieces are the screen poles 5, in any number and spaced from each other at any chosen distance. Below the lower pairs of 20 wale-pieces 4 the ends of the poles pass through the mattress 6 and into the river bed 1. Rocks are placed on the mattress for the purpose of weighting down or sinking and holding the mattress in place upon the 25 river bed. Any suitable arrangement of rock ballast may be employed for the purpose stated but as the mattress is illustrated in the drawings in its floating position the rocks are not shown thereon. Through the 30 lower ends of the screen poles 5 below the mattress there is passed the securing flexible rod, chain or cable 8, 8', 8''.

35 In Figure 1 it will be noted that certain of the screen poles just below the lower wale-pieces 4 are connected with each other by means of batting bars 9, and that the sets of screen poles thus coupled are hung to the wale-pieces 4 by wires 10. The battings and the wire connections are temporary 40 fastenings to hold the screen poles in proper attitude and to assist in supporting the mattress, preparatory to the operation of sinking the mattress. While the batting bars 9 and the temporary wire connections 10 are 45 shown only in Figure 1 it is to be understood that these same temporary connections are intended to be used with the form of the invention shown in Figure 6.

50 Considering the drawings Figures 6 to 10, it will be noted that in Figure 6 the river bed 1 and the regular piling 2, together with the wale-pieces 3 and 4 in parallel pairs are the same as before, as is also the mattress 6. In this form of the invention the screen 55 poles 11 have at their lower ends the pivoted toggles 12 held by bolts 13. It will be understood that the toggles 12 can be arranged lengthwise against the screen pole as illustrated in Figure 8, and while in such position the pole bearing the toggle may be thrust through the mattress. After the end of the pole bearing the toggle has passed through the mattress, the toggle is turned crosswise of the end of the pole, which plainly cannot 60 now be withdrawn through the mattress.

It is held to be within the purview of this invention to provide the end of the screen pole with two toggle members 12 one on either side of the end of the pole.

As previously stated herein the two forms 70 of the screen pole securing devices may be employed together or separately. The operation and effect of both is the same. After the ends of the screen poles 5 have been passed through the mattress 6, the flexible 75 rods, 8, chain 8' or cable 8'' below the mattress prevents the withdrawal of the rods while allowing a limited vertical movement of either rods or mattress. The same effect is produced after the toggles 12 have been 80 turned crosswise of the ends of the poles below the mattress, and any pole may rise slightly, assuming that a stone might be encountered in the river bed which would prevent the end of the pole from passing into 85 the river bed as far as the others. The remaining poles will not be disturbed, and it is believed to be equally apparent from the drawings and the foregoing explanation that the mattress may rise slightly at any 90 part without displacing the poles at that part.

Having now described this invention, I claim:—

1. In a construction of the character described, the combination with fixed piles, of wale-pieces spaced apart and secured to the piles, a mattress, screen poles supported vertically by the said wale-pieces and passing through the said mattress, and means connected with the ends of the said poles below the mattress whereby the said poles are secured against removal and the said mattress allowed a movement up and down on the poles. 95

2. In a construction of the character described, the combination with fixed piles, of wale-pieces spaced apart and secured to the piles, a mattress, screen poles supported vertically by the said wale-pieces and passing through the said mattress, means connected with the ends of the poles below the mattress whereby the said poles are secured against removal and are permitted a limited movement reciprocally through the mattress, and temporary connections arranged between the said poles and the said wale-pieces. 100

3. In a construction of the character described, the combination with fixed piles, of wale-pieces spaced apart and secured to the piles, a mattress, screen poles supported vertically by the said wale-pieces and passing through the said mattress, means connected with the ends of the poles below the mattress whereby the said poles are secured against removal and are permitted a limited movement reciprocally through the mattress, and means for temporarily connecting the said poles with each other and with one of the 105 said wale-pieces. 110

4. In a construction of the character described, the combination with fixed piles, of upper and lower wale-pieces secured to the piles, a mattress, screen poles supported vertically by the said wale-pieces and passing through the said mattress, means connected with the ends of the poles below the mattress whereby the said poles are secured against removal and are permitted a limited movement reciprocally through the mattress, and means for temporarily connecting the said poles with each other and with a lower wale-piece.

5. In a construction of the character described, the combination with fixed piles, of

upper and lower horizontally disposed parallel wale-pieces secured to the piles, a mattress, screen poles supported vertically by said wale-pieces and passing through the mattress and toggle members pivotally connected midway between their ends to the lower ends of the screen poles below the mattress, said toggle members normally lying lengthwise along the poles and adapted to be turned crosswise of the poles whereby the poles are secured against removal but have a limited vertical movement through the mattress.

In testimony whereof I affix my signature.
HOWARD N. MOODY.
